US0D1049381S

(12) **United States Design Patent** (10) **Patent No.:** **US D1,049,381 S**
(45) **Date of Patent:** **** Oct. 29, 2024**

(54) **WEARABLE COMPRESSION DEVICE**

(71) Applicant: **Innovation Lab, LLC**, Newport Beach, CA (US)

(72) Inventors: **Joseph Paul Randolph**, Seal Beach, CA (US); **Myong Kim**, Tustin, CA (US)

(73) Assignee: **Innovation Lab, LLC**, Newport Beach, CA (US)

(**) Term: **15 Years**

(21) Appl. No.: **29/798,154**

(22) Filed: **Jul. 6, 2021**

(51) LOC (14) Cl. **24-02**

(52) U.S. Cl.

USPC **D24/165**

(58) **Field of Classification Search**

USPC D24/107, 108, 109, 111, 134, 137, 146, D24/158, 164, 165, 166, 167, 168, 169, D24/177, 185, 186, 187, 216, 223, 231, D24/232

CPC A61B 5/00; A61B 5/0205; A61B 5/091; A61B 5/6824; A61B 5/0022; A61B 5/0006; A61B 5/0008; A61B 5/02108; A61B 7/04; A61B 7/00; A61B 7/003; A61B 8/00; A61B 8/08; A61B 8/02-06; A61B 8/065; A61B 8/52; A61H 2230/04; H04R 1/46; B06B 1/00; G01H 3/00; G01H 3/12; G01H 9/00; G01N 29/265

(57) **CLAIM**

The ornamental design for a wearable compression device as shown and described.

DESCRIPTION

FIG. 1 is a top, front, and right side perspective view of a first embodiment of a wearable compression device of our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines illustrate portions of the wearable compression device that form no part of the claimed design.

1 Claim, 7 Drawing Sheets
